HELICOPTER DEVICE.

George de Bothezat, New York, N. Y., assignor
to Helicopter Corporation of America, Long
Island City, N. Y., a corporation of New York

Application December 30, 1937, Serial No. 182,400

7 Claims. (Cl. 244—17)

This invention relates to flying devices of the helicopter type and particularly to such a device adapted for lifting a part or all of the weight of the user, and is directed to improvements on the 5 helicopter device disclosed in my co-pending application Serial No. 92,307.

The primary object of the invention is to provide a helicopter device permitting the user to walk and run faster and jump higher than normally, and which, when desired, will lift and 10 transport the user under simple control and manipulation by him.

Another object of the invention is to provide such a device which can stand on the ground by 15 itself, which will protect the feet and legs of the user in case of a rough landing and which will nevertheless permit free leg movements of the user when he desires to walk or run with the device along the surface of the ground.

20 Still another object of the invention is to provide in such a device an improved construction for mounting and driving the lifting screws.

Further objects of the invention, particularly 25 in providing such a helicopter device which will be simple and light in structure, inexpensive in cost, and efficient in operation, will appear from the following specification taken in connection with the accompanying drawings, in which

Fig. 1 is a side elevational view showing one 30 form of the machine of this invention standing on the ground;

Fig. 2 is a perspective view of the frame for such machine;

Fig. 3 is an elevational view of the machine 35 with the user standing on the ground;

Fig. 4 is a vertical section along the line 4—4 of Fig. 1 illustrating the mounting and driving construction of the screws;

Fig. 5 is a horizontal section along the line 40 6—6 of Fig. 4 in reduced scale;

Fig. 6 is an alternate construction for mounting and driving the screws;

Fig. 7 is another alternate construction for 45 mounting and driving the screws;

Fig. 8 is a horizontal section along the line 8—8 of Fig. 7 in reduced scale;

Fig. 9 is a horizontal section along the line 45 9—9 of Fig. 7 in reduced scale;

Fig. 10 is a horizontal section along the line 50 10—10 of Fig. 7 in reduced scale;

Fig. 11 is a side elevational view showing another form of the machine of this invention standing on the ground;

Fig. 12 is a plan view of the machine of Fig. 11;

Fig. 13 is a front elevational view of the machine of Fig. 11, with parts omitted for clarity;

Fig. 14 is an enlarged elevational view of the lower portion of the machine of Fig. 11; and

Fig. 15 is a plan view of the portion of the 60 machine shown in Fig. 14.

In a specific embodiment of the invention shown in Fig. 1, the paired helicopter screws 10, 11 are driven by the air-cooled internal combustion engine 12 located below the screws. The engine 12 is of the two cylinder type and has its 5 crankshaft connected to the screws 10, 11 through reducing gears, as will be described hereafter, so that the screws rotate in opposite senses at speeds lower than the engine speed.

Above the upper screw 10 is a small air screw 13 which is rotated at a high speed, such as the 10 engine speed. This air screw 13 directs a flow of air across the engine 12 for cooling the same. The diameter of this screw 10 is preferably 15 slightly larger than the outer diameter of the 15 engine.

The whole system of screws and engine is mounted at the top of a frame 14 made of two spaced uprights 15 and 16 connected by cross pieces 17, 18, 19 and 20, the uprights and cross 20 pieces being preferably of hollow steel tubing. Each of the uprights 15 and 16 has a portion shaped like a U lying on its side with the yoke 21 thereof to the front and with its side 22 above the other side 23. At the rear of the upper side 25 22 each upright of the frame extends upwardly and slightly forwardly, as at 24. At the top of the uprights they are attached to the under side of the engine 12.

Cross pieces 19 and 18 are positioned respectively at the forward end and slightly above the rear end of each upper side 22 of the U portions. Extending downwardly from the cross piece 18, preferably at its mid length, is a tube 25; and from the lower end of tube 25 to cross piece 19 35 is a tube or member 26 on which is mounted a saddle 27 for supporting the user of the device. To cross piece 18 is suitably secured a belt 28 which is to be strapped around the waist of the user. Cross piece 20, connecting the yokes 21 of 40 the U portions, may serve as a foot rest for the user. Cross piece 17 is near the top of the uprights.

With a frame of the above construction the device will support itself upon the ground as 45 shown in Fig. 1, while enabling the user to stand with the device (as shown in Fig. 3) when the air screws 10 and 11 are running and to walk and jump with it without having it impair his leg movements. In flight, the user may set on 50 the saddle 27 and may also rest his feet upon the cross piece 20, as shown in Fig. 1. In landing with the device, as in a jump, the user may land on his feet, but in the event of a rough or heavy landing, the lower sides 23 of the frame 55 contact with the ground before any injury to the user's legs results. In such case the resiliency of the frame, and particularly of the lower sides 23, absorbs the shock of the landing. If the user so desires he may land with his feet resting upon 60

the cross piece 20 and thereby have the frame absorb the entire shock of landing.

Figs. 4 and 5 illustrate a construction for mounting and driving the air screws. The drive shaft 30 of the engine extends upwardly through a gear case 31, the lower portion 31a of which is secured to the top of the engine casing as at 12a (Fig. 2). The upper portion 31b of gear case 31 is cylindrical in shape. The two portions 31a and 31b are connected by a horizontal portion 31c. The shaft 30 is enclosed by a tubular member 32, the lower end of which, 32a, is secured to the horizontal portion 31c of the gear case and is crescent shaped as shown in Fig. 6, so as to accommodate the reduction gearing 33 in the open part of the crescent. This reduction gearing 33 consists of a gear 34 mounted upon and secured to the drive shaft 30, of gears 35a and 35b mounted upon and secured to a vertical stub shaft 36 having stationary bearings, the lower end of shaft 36 being seated in the horizontal portion 31c of the gear case and the upper end of the shaft being seated in a horizontal extension 32c of tubular member 32, and of annular gear 37 secured to the hub 38 of air screw 11. Gear 34 meshes with gear 35a and gear 35b meshes with annular gear 37. Gears 34 and 35b have a relatively small number of teeth, while gears 35 and 37 have a relatively large number of teeth. This reduction gearing 33 produces a direction of rotation of air screw 11 which is opposite to that of shaft 30.

Hub 38 rotates about tubular member 32 and is mounted and supported thereon by the frictionless bearing 39. This bearing is of a type which withstands both axial and radial forces.

Gear case 31 is preferably provided with an annular ring 31d that fits between cylindrical portion 31b of the case and a cylindrical lip 38a at the underside of the hub, thereby completely enclosing the gearing in gear case 31. Suitable bearings 40 may be provided between the ring 31d and the hub 38.

Drive shaft 30 has a vertical extension 30a, connected thereto by a flexible coupling 30b.

Shaft extension 30a is enclosed by a tubular member 41 having a shoulder 41a which rests upon the upper end of tubular member 32, and having a lip 41b which fits tightly around the inside of member 32. The upper end of member 41 bells out as at 41c, to form a housing for epicyclic or planetary reduction gearing 42. This consists of the annular gear 43 secured to housing 41c, of gears 44a and 44b mounted upon and secured to a shaft 45 and of annular gear 46 secured to the hub 48 of air screw 10. Shaft 45 is rotatably mounted upon an arm 47 which is secured to and rotates with the shaft extension 30a. Gear 44a meshes with annular gear 43 and gear 60 44b meshes with annular gear 46. The train value of the planetary gearing 42 is such that the direction of rotation of the air screw 10 is the same as that of shaft 30.

Hub 48 rotates about shaft extension 30a and is mounted and supported thereon by the frictionless bearing 49. This bearing is of a type which withstands both axial and radial forces. This hub 48 is preferably provided with a bearing 50 between a cylindrical lip 48a at the underside of the hub and the upper end of housing 41c.

The small air screw 13 is secured directly to shaft extension 30a above the hub 48. The air screw 13 thus rotates in the same direction, and with the same speed, as drive shaft 30.

75 Fig. 6 illustrates an alternate construction.

The drive shaft 60 of the engine extends upwardly through a member 61, the lower portion 61a of which is secured to the top of the engine. The hub 62 of air screw 11 is rotatably mounted upon the upper portion 61b of member 61 by means of the frictionless bearing 63. This bearing is of a type which withstands both axial and radial forces.

Above hub 62 is a tubular member 64 surrounding shaft 60 and also surrounding shaft extension 60a, the latter being connected to shaft 60 by the flexible coupling 60b. The lower end of member 64 is bell-shaped, as at 64a to provide a housing for the epicyclic or planetary gearing 65. This gearing consists of annular gear 66 secured to housing 64a, of gears 67a and 67b mounted upon and secured to a shaft 68 and of an annular gear 69 that is secured to the hub 62 of air screw 11. Shaft 68 is rotatably mounted upon an arm 70 which is secured to and rotates with shaft 60. Gear 67a meshes with annular gear 66 and gear 67b meshes with annular gear 69. The train value of the planetary gearing 65 is such that, assuming tubular member 64 remains stationary, the direction of the rotation of the air screw 11 is opposite to that of shaft 60.

Hub 62 is preferably provided with a bearing 71 between a cylindrical lip 62a at the upper side of the hub and the lower end of housing 64a.

The upper portion of tubular member 64 is bell-shaped, as at 64b, to provide a housing for the epicyclic or planetary reduction gearing 75. This consists of annular gear 76 secured to housing 64b, of gears 77a and 77b mounted upon and secured to a shaft 78 and of an annular gear 79 secured to the hub 72 of air screw 10. Shaft 78 is rotatably mounted upon an arm 80 which is secured to and rotates with shaft extension 60a. Gear 77a meshes with annular gear 76 and gear 77b meshes with annular gear 79. The train value of the planetary gearing 75 is such that, assuming tubular member 64 remains stationary, the direction of the rotation of the air screw 10 is the same as that of shaft 60. Thus, the train value of the planetary gearing 75 is in the opposite sense relative to that of the planetary gearing 65; that is, if the train value of the gearing 65 is less than one, the train value of the gearing 75 is greater than one. This relationship in the train values of gearing 65 and 75 is obtained in the construction illustrated by having corresponding annular gears 66 and 76 of the two gearings of different diameter, the former smaller than the latter.

Hub 72 rotates about shaft extension 60a and is mounted and supported thereon by the frictionless bearing 83. This bearing is of a type which withstands both axial and radial forces. Hub 72 is preferably provided with a bearing 81 between a cylindrical lip 72a at the under side of the hub and the upper end of housing 64b.

The small air screw 13 is secured directly to shaft extension 60a above the screw 10. The air screw 13 thus rotates in the same direction and with the same speed as drive shaft 60.

With the construction shown in Figs. 4 and 5, the number of revolutions of each of the air screws 10 and 11 bears a fixed relation to the number of revolutions of the engine, and thus, to each other. That the speed of screw 11 bears a fixed relation to the speed of shaft 30 is obvious from the character of the gearing 33. That the speed of screw 10 bears a fixed relation to the speed of shaft 30 is due to the fact that one of the non-planetary gears—the annular gear 43—is 75

maintained stationary relative to the engine case. This is effected by means of tubular members 41 and 32 and by the gear case 31.

The feature of the construction shown in Fig. 6 is that maximum efficiency is obtained for the lifting screws 10 and 11. This is due to the fact that, with such a construction, there is no rotation of the resulting slip-stream produced by the two oppositely rotating lifting screws 10 and 11, with the result that the race-rotation loss (i. e., the loss due to the rotation of the slip-stream), is entirely eliminated. Rotation of the resulting slip-stream is eliminated by the action of the tubular member 64.

15 In explanation, since lifting screws 10 and 11 rotate in opposite directions, the air resistance torques of the screws act in opposite directions. In other words, the reaction torque applied to member 64 as an incident in driving air screw 10, is in the opposite direction to the reaction torque applied to the same member as an incident in driving air screw 11. These reaction torques thus tend to balance one another. If the air resistance torques of the lifting screws are equal in magnitude, the reaction torques applied to member 64 are equal in magnitude but opposite in direction, and thus are exactly balanced so that tubular member 64 remains stationary. If the air resistance torques of the lifting screws are not exactly equal, so that there is a slight difference in magnitude between the reaction torques applied to member 64, the tubular member 64 will rotate slightly. This rotation of member 64 tends to equalize the air resistance torques. Thus, the torques of the lifting screws are equalized.

It is to be noted that in the construction illustrated in Fig. 4, the gears 35a and 35b and the stub shaft 36 do not transmit vertical stresses from the horizontal portion 32c to the horizontal portion 31c, such forces being carried by the stationary vertical portions 32a. If desired, however, the stub shaft 36 may be arranged to carry some of such vertical stresses, and thereby obtain a better balanced condition of stresses in gear casing 31 and member 32. For example, stub shaft 36 may be fitted into bearings at the ends thereof of a type that withstands both axial and radial forces. Alternately, the ends of the stub shaft 36 may be stationary and suitably fitted or secured to the horizontal portions 31c, 32c, with the gears 35a, 35b, suitably rotatably mounted on shaft 36. In another alternate arrangement shaft 36 may be dispensed with and the hubs of gears 35a, 35b extended axially to cooperate with, or form part of, bearings which support these gears between horizontal portions 31c and 32c and which are of the type which withstands both axial and radial forces.

Figs. 7, 8, 9 and 10 illustrate an alternate construction for mounting and driving the air screws. In this construction the engine 112 is positioned between the air screws 10 and 11, and in addition, the engine cooling screw 13 is positioned between the two air screws.

65 The engine 112, and the screws driven thereby, are secured to the top of the frame 14 (Figs. 1 and 3) through a member 131, the lower portion 131a of which is provided with suitable means for connecting it to the frame 14. An upper and horizontal portion or portions 131c of member 131 is provided with a plurality of bearings 200 for supporting the lower ends of a similar number of short vertical shafts 136. Preferably there are three shafts 136, and thus three bearings 200, arranged equi-distantly about the engine drive

shaft 130, as shown in Fig. 10. The upper ends of these shafts 136 cooperate with bearings 201 which are secured to the under side 202 of the engine casing 203. Each of the bearings 200 and 201 is of the type that withstands both axial and radial forces.

The hub of air screw 11 rotates about a vertical portion 131b of member 131 and is mounted and supported thereon by a frictionless bearing 205. This bearing is of the type that withstands both axial and radial forces.

15 The engine 112 drives air screw 11 through the reduction gearing 133. This consists of a small gear 134 mounted upon and secured to a portion of the vertical drive shaft 130 which extends below the gear casing 203, of an annular gear 137 secured to or formed upon an axial extension 206 of hub 204, and of a plurality of sets of gears 135a, 135b. Each such set, of which there are three in the construction shown, consists of a 20 relatively large gear 135a and a somewhat smaller gear 135b, each formed upon, or secured to, shaft 136, with gear 135a meshing with gear 134 and with gear 135b meshing with annular gear 137. This reduction gearing 133 produces a direction 25 of rotation of air screw 11 which is opposite to that of shaft 130.

It is preferred to enclose gearing 133. In the construction shown, this is effected by a downwardly extending lip 207 provided on the engine 30 casing 203, which lip is overlapped by an upwardly extending lip 208 provided on the hub extension 206. A suitable bearing 209 may be provided between the lips 207 and 208. A cap 210 may be provided to enclose the under side of 35 the gearing 133, this cap fitting closely against the inside of the vertical portion 131b of member 131.

40 The air screw 10 and the engine cooling screw 13 are positioned above engine 112. These screws, together with the gearing therefor, are attached to the engine as a unit by the clamping nut 215 and the bolts 219. Clamping nut 215 engages a threaded portion of the drive shaft 130 which extends above the upper side 216 of the engine 45 casing 203, and serves to axially secure a rotating member 217 against the shoulder 218 formed on drive shaft 130. Bolts 219, positioned around the engine casing, secure a stationary member 50 220 to such casing.

Above stationary member 220 is positioned a second stationary member 221. Members 220 and 221 are secured together by a plurality of shafts 222 (preferably three, as illustrated, see Fig. 9), the lower and upper ends of each of 55 222 which are respectively journaled in bearings 223 and 224, these bearings being secured respectively on members 220 and 221, and being of the type which withstands both axial and radial forces.

The hub 230 of upper air screw 10 rotates inside an upwardly extending lip 231 on stationary member 221, and is mounted and secured thereon by the frictionless bearing 232, this bearing being of the type that withstands both axial and radial forces.

65 Air screw 10 is driven by engine 112 through the epicyclic or planetary reduction gearing 142. This consists of the annular gear 143 secured to stationary member 221, of an annular gear 146 formed upon, or secured to, the inside of hub 230 70 and of a plurality of sets of gears 144a, 144b. Each such set, of which there are three in the construction shown, consists of a relatively large gear 144a and a somewhat smaller gear 144b, each formed upon, or secured to, a sleeve 235, 75

with gear 144a meshing with annular gear 143 and with gear 144b meshing with annular gear 146. Sleeve 235 is rotatably mounted upon a vertical rod 236 which extends through apertures 5 in two radial arms 237, 238 formed on rotating member 217, this member being secured to drive shaft 130, as by the key 239, so as to rotate therewith. The lower end of rod 236 is provided with a flanged head 240 which sits in a suitable recess 10 in arm 237. The upper end of rod 236 is threaded to receive the nut 241 which secures the rod in place. Between the rod 236 and sleeve 235 are two suitable frictionless bearings 242 and 243, the former at the bottom and the latter at the top 15 of the sleeve. The diameter of the rod 236 preferably increases, as at 244, just below the upper bearing 243 so as to position the sleeve 235 and its gears 144a, 144b between the arms 237, 238.

The train value of the planetary gearing 144 20 is such that the direction of rotation of the air screw 10 is the same as that of shaft 130.

The hub of the engine cooling screw 13 is a ring 250 which rotates about a downwardly projecting lip 251 on the stationary member 221, and 25 is mounted and secured thereon by the frictionless bearing 252.

The engine cooling screw 13 is driven by engine 112 through the gearing 255. This consists 30 of a gear 256 formed upon, or secured to, rotating member 217, of an annular gear 257 formed upon, or secured to, an annular ring 258 which is secured to ring 250 at the under side thereof, and of a plurality of sets of gears 260a, 260b. Each such 35 set, of which there are three in the construction shown, consists of a gear 260a and a somewhat larger gear 260b, each formed upon, or secured to, one of the shafts 222, with gear 260a meshing with gear 256 and with gear 260b meshing with annular gear 257. The train value of this gearing 255 is such that the speed of the engine cooling screw is substantially greater than that of the air screws 10 and 11, and is of substantially the 40 same speed as that of drive shaft 130. The direction of rotation of the engine cooling screw 13, in conjunction with the angle of its blades, is such as to force air from above the screw down over the cylinder heads of the engine.

With the arrangement of the engine 112, air screws 10 and 11 and engine cooling screw 13 as 50 illustrated in Figs. 7-10, it is desirable to provide a cowling 270 about the engine extending upwardly past the cooling screw 13 for directing over the cylinder heads of the engine the air currents which such screw produces. Cowling 270 55 may be suitably secured to the ends of the cylinder heads, as at 271, and may be formed in suitable sections to facilitate attachment and removal. If desired, baffles may be provided inside the cowling for further directing the cooling 60 currents over the cylinder heads and for preventing the escape of cooling currents between the cylinders. Also, if desired, the inner portion of screw 11 may be covered with a light metallic sheet, such as duralumin, to protect that portion 65 of the screw from the exhaust heat and fumes from the engine. Such covering may, for example, extend outwardly for about 20% of the radius of the screw.

In order to completely enclose the gearing 142 70 and 255 in those places where it is not already enclosed by the construction heretofore described, the stationary member 220 is provided with an upwardly extending lip 275 which overlaps the annular ring 258. A suitable bearing 276 may be 75 provided between the lip 275 and the ring 258.

Also, the aperture in hub 230 in axial alignment with the drive shaft 130 may be enclosed by a removable cap 278.

The drive for the air screws shown in Figs. 7-10 is in some respects similar to that shown in Figs. 4 and 5. Thus, in each construction the number of revolutions of each of the air screws bears a fixed relation to the number of revolutions of the engine, and thus to each other. Further, this relationship is obtained in each construction by an epicyclic gear system for the upper air screw 11 and a non-epicyclic gear system for the lower air screw 10.

One of the features of the construction of Figs. 7-10 is a well balanced gear drive providing a balanced distribution of the lifting forces about the engine drive shaft. Another feature is the saving in weight and space which results from this construction. Still another feature is the efficient manner in which the engine is cooled, thus enabling a maximum of the developed power of the engine to be employed for lifting purposes.

Figs. 11-15 illustrate a modified form of the invention shown in Figs. 1-3, together with the construction for mounting and driving the air screws which is shown in Figs. 7-10. This mounting and driving construction is generally designated at 300.

The frame 314 of the machine is similar to the frame 14 shown in Figs. 1-3, to the extent that it includes two spaced up-rights 315 and 316 connected by cross-pieces 317, 318, 319 and 320, with the up-rights each having a portion shaped like a U lying on its side with the yoke 321 thereof to the front and with its side 322 above the other side 323, all corresponding respectively to 15, 16, 17, 18, 19, 20, 21, 22 and 23 of Figs. 1-3. Frame 314 is also provided with a saddle and belt similarly as in Figs. 1-3.

Frame 314 includes in addition a guard for protecting the user in the event the machine should turn over frontwards, as for example, when making a landing. This guard consists of two substantially vertical arc-shaped members 325, 326, positioned in front of the user with the upper and lower ends of each such member merging with, or being connected to, the upper and lower ends, respectively, of the corresponding up-rights 315, 316 of the frame 314. The upper ends of up-right 315 and member 325 are preferably connected to the upper ends of upright 316 and member 326, as by the cross-pieces 327. These strengthen the framework and provide a point of connection with the motive unit 300.

The lower end of each member 325, 326 preferably includes a horizontal portion 333 parallel to, in the same plane as, and positioned a short distance from the portion 323 of the corresponding up-right, with the rear ends of such horizontal portions 323 and 333 connected by a short transverse portion 334. The portions 333 thus function similarly as portions 323 in enabling the machine to support itself upon the ground, as shown in Fig. 11 while also enabling the user of the machine to stand when the air screws 10, 11 are running, and to walk and jump with it without having the framework impair his leg movements. These portions 323 and 333 also prevent injury to the user's legs when landing with the machine, similarly as with the portions 23 of Fig. 1.

In addition, the lower end portions 323, 333 at each side of the machine support a plurality of transverse rollers 335 over which is mounted an endless belt or caterpillar tread 336. This construction, providing what may be termed "cater-

"pillar skis" at each side of the machine, facilitates landings which are made with a slight forward motion, and also facilitates handling the machine upon the ground, such as rolling it to and from its hangar, etc.

The frame 314 preferably includes two rearwardly extending members 340, 341, connected respectively at their front ends to cross-pieces 317, 319. Upon members 340, 341 are mounted two fins 342, 343. Fin 342 is a substantially vertical fin positioned inside the slip stream of the air screws 10, 11, and serves to damp rotary motion of the machine around a vertical axis, both when hovering and when in forward motion, and also serves to secure an even forward motion. If desired, the fin may be mounted at a small angle from the vertical, the direction and amount of the angle being such as to produce, as a result of the air flow down past fin 342, a force which just neutralizes any force which might tend to cause rotation of the frame of the machine about a vertical axis.

Fin 343 is a substantially horizontal fin positioned outside the slip stream of the air screws 10, 11, but sufficiently close thereto to have a small current of air impinged upon its upper surface. This fin 343 serves to provide stability about a transverse horizontal axis and to prevent nose diving of the machine in flight. If desired, the fin may be mounted at a small angle to the horizontal to produce a slight negative lift by virtue of the air flow down past the fin.

While fins 342 and 343 are illustrated as stationarily mounted upon the rearwardly extending members 340, 341, either or both of such fins may be pivotally mounted—fin 342 about a vertical axis and fin 343 about a horizontal axis—in any suitable manner, with suitable controls therefor extending to the user so that he may adjust them in flight, as desired.

I claim:

1. In a machine of the helicopter type having a plurality of lifting screws driven by an internal combustion engine in such manner that the lifting torques substantially balance, and in which said screws and engine are positioned above the head of the operator; a frame fastened to said engine extending downwardly therefrom and having means for supporting at least a part of the weight of the operator by the vertical thrust of said lifting screws, said frame extending downwardly below the waist-line of the operator in two portions, one at either side of the operator and at a sufficient distance apart as not to interfere with the free leg movements of the operator, and terminating approximately at the horizontal plane in which lie the operator's knees when, in using the machine, he is in standing position.

2. A device as set forth in claim 1 in which the downwardly extending portions of the frame are each shaped like a U lying on its side with the yoke thereof to the front and with its sides in substantial vertical alignment, the lower side of the U being in approximately the horizontal plane of the knees of the operator when, in using the machine, he is in standing position.

3. In a machine of the helicopter type having a plurality of lifting screws driven by an internal combustion engine in such manner that the lifting torques substantially balance and in which said screws and engine are positioned above the head of the operator, a frame fastened to said

engine comprising two spaced uprights each having its lower portion shaped like a U lying on its side with the yoke thereof to the front and with its sides in vertical alignment, the upper portion of each upright extending from the rear portion of the upper side of said U portion upwardly and slightly forwardly to the engine; cross pieces connecting said uprights, two of said cross pieces being positioned near the front and rear portions of the upper sides of said U portions; and a saddle for the operator supported between said uprights by said two cross pieces, the heights between the two sides of each of said U-shaped portions and between the saddle and the lower side of each of said U-shaped portions being such that a substantial portion of the legs of the operator extend below the lower side of each of said U-shaped portions when the operator is in standing position astride the saddle, thereby enabling the operator to walk or jump with the machine as well as ride during flight.

4. A device as set forth in claim 1 in which the frame includes members for guarding the operator of a machine, said members extending from the top to the bottom of the said frame in front of the operator.

5. In a machine of the helicopter type having a plurality of lifting screws driven by engine means in such manner that the lifting torques substantially balance and in which said screws and engine means are positioned above the head of the operator, a frame fastened to said engine means and extending downwardly therefrom, the lower portion of said frame including two U-shaped portions positioned on either side of the operator with the yokes of such portions to the front and with the lower sides thereof positioned at about the level of the operator's knees when, in using the machine, he is in standing position, said frame also including two arcuate guard members positioned in front of the operator with the upper and lower ends of said guard members secured respectively to the top of said frame and to the lower sides of said U-shaped portions.

6. In a machine of the helicopter type having a plurality of lifting screws driven by engine means in such manner that the lifting torques substantially balance and in which said screws and engine means are positioned above the head of the operator, a frame fastened to said engine means and extending downwardly therefrom, the lower portion of said frame including two U-shaped portions positioned on either side of the operator with the yokes of such portions to the front and with the lower sides thereof positioned at about the level of the operator's knees when, in using the machine, he is in standing position, the lower side of each of said U-shaped portions including a plurality of rollers mounted thereon and an endless belt extending around said rollers.

7. A device as set forth in claim 5 in which the lower ends of said guard members extend alongside, parallel to, and spaced a short distance from, the respective lower sides of said U-shaped portions, and in which a plurality of rollers are mounted between the lower end of each guard member and the corresponding lower side of the U-shaped portions, with an endless belt extending around said rollers at each side of said frame.

GEORGE DE BOTHEZAT.
